Design for Stoves
Patented Jan 29, 1874

Des. 347

Conrad Harris & Paul W. Joiner of Cincinnati, O.
Setters Patent No. 347 - dated Jan. 28, 1851.

The Schedule referred to in these Setters Patent and making part of the same.

To all whom it may concern:

Be it known, that we,

Conrad Harris & Paul W. Joiner, both of Cincinnati, Hamilton County, State of Ohio, have invented a new ornamental Design for Coal & wood parlor stoves, and we do hereby declare that the following is an exact description of the same, to wit:

On the annexed drawing is the surface and front view. B side view. C top view. D top of the arm. E side view of the foot. F panel in front (enclosed in the drawings with red ink,) to be used in the Coal stove for a door. G, G, enclosed the same as F, to be used for doors on the coal stove. H panel on the side (also enclosed with red ink in the drawings) to be used for a door on the wood stove.

What we claim as our invention, and desire to secure by Setters Patent, is the combination and arrangement of the above represented scrolls, foliage, figures and mouldings, into an ornamental design for Coal and wood parlor stoves, to be known and called Harris & Joiner's patent Coal & wood parlor stove.
